UNITED STATES PATENT OFFICE.

IRVING G. PLATT, OF WATERBURY, CONNECTICUT.

METHOD OF FORMING RIVETS.

SPECIFICATION forming part of Letters Patent No. 449,699, dated April 7, 1891.

Application filed April 19, 1890. Renewed February 2, 1891. Serial No. 379,917. (No model.)

To all whom it may concern:

Be it known that I, IRVING G. PLATT, a citizen of the United States, and a resident of Waterbury, in the county of New Haven and 5 State of Connecticut, have invented certain new and useful Methods of Forming Rivets, of which the following is a specification.

My invention relates to an improved process or method of forming slotted rivets, and 10 more particularly to that kind or class thereof which are formed from a piece of wire and adapted to cut or pierce their own way through the fabric or other article to which they are attached.

15 Heretofore in constructing rivets from wire or like material it has been the practice to remove so much of the metal from the center as will sufficiently sharpen or thin the ends of the prongs to enable the latter to pierce 20 their way through the material to which they are applied, or to first remove the greater portion of the metal from the center of the shank of the rivet and subsequently chisel the ends of the prongs on the outer side; but such end 25 is accomplished at the expense of the holding-surfaces of the prongs, as it is obvious that the greater the amount of metal removed from the center toward the outer surfaces of 30 the prongs the less holding-surface there will be, which is of course due to the cylindrical shape of the metal from which the prong is constructed.

35 The object of my invention is to form the rivet in such a way that the central portion of the rivet, which is necessarily greatest in width, will be utilized as the holding-surfaces of the shank; and with such end in view my method consists, substantially, in first striking up or otherwise forming the head or flange 40 upon one end of the shank, in slitting or slotting the shank of the rivet, then spreading the prongs apart, and finally swaging or cutting away the outer surface of the prongs.

45 To more fully explain my improved method of forming rivets, reference is had to the accompanying drawings, in which—

Figure 1 is a view in elevation of the rivet after the head has been formed thereon and the shank slitted or slotted. Fig. 2 is a plan 50 view thereof. Fig. 3 is a view showing the rivet in its second stage, the prongs having been spread apart. Fig. 4 is a plan view thereof.

Fig. 5 is a view in elevation of the finished rivet, the outer surfaces having been swaged or cut away after the prongs have been spread 55 apart, as shown in Fig. 3; and Fig. 6 is a plan view of the finished rivet as shown in elevation in Fig. 5.

A represents the head of the rivet, formed of wire or similar material, and B the shank 60 thereof, provided at its center with a slit or slot *a*, in forming which latter the least amount possible of metal is removed, the object being to retain to the greatest extent the metal occupying the center of the shank, in order to 65 utilize as holding-surfaces the greatest width of metal. After the shank has been provided with said slits or slots *a* the prongs *b b* are separated or spread apart by suitable means— 70 as, for instance, by a tool of wedge shape, (not shown,) the rivet assuming the shape as shown in Fig. 3 of the drawings. The outer surfaces of these prongs are then cut away, the effect of which is to form each prong of wedge shape, at the same time retaining or 75 utilizing the central portion of the rivet and forming the piercing ends of a width equal or nearly equal to the diameter of the shank before being slotted. Instead of cutting away the outer surfaces of these prongs, as above 80 described, the same end may be accomplished by removing a somewhat greater amount of metal from the center of the rivet, and subsequently swaging the prongs to such an extent that they will be the same or substan- 85 tially the same in width as in the case of removing the minimum amount of metal from the center and subsequently cutting away the outer surfaces, the flattening or spreading of the metal by the process of swaging compen- 90 sating for the extra amount of metal removed from the center.

In swaging or removing the outer portions of the shanks, as above described, I prefer to form them concave in shape, in order to secure an extra thickness of metal on the vertical edges of the shanks and the resulting increase in strength.

It will of course be understood that I do not limit my claim to the steps in the succession as I have above described, as it may at times be desirable to remove the outer surfaces of the prongs before spreading them apart; or, again, it may be necessary or found

desirable to remove this outer surface before the shank is slotted or slotted, and this without in any way affecting the result or the spirit of my invention; but

5 What I claim as new, and desire to secure by Letters Patent, is—

1. The method or process hereinbefore described of forming slotted rivets, which consists in forming the flange or head upon one end of the shank, slitting or slotting the latter, spreading the prongs apart, and so removing the outer surfaces of said prongs as to form them concave in shape.

10 2. The method hereinbefore described of

forming slotted rivets, which consists in forming the flange or head upon one end of the shank, slitting or slotting the latter, spreading the prongs apart, and so removing the outer surfaces of said prongs as to form them concave in shape.

Signed at New York, in the county of New York and State of New York, this 17th day of April, A. D. 1890.

IRVING G. PLATT.
